UNITED STATES PATENT OFFICE.

DANIEL B. LUTEN, OF INDIANAPOLIS, INDIANA.

SYSTEM OF REINFORCEMENT FOR CONCRETE AND SIMILAR STRUCTURES.

No. 830,483.

Specification of Letters Patent.

Patented Sept. 4, 1906.

Application filed February 13, 1905. Serial No. 245,366.

To all whom it may concern:

Be it known that I, DANIEL B. LUTEN, a citizen of the United States, residing at Indianapolis, Indiana, have invented certain new and useful Improvements in Systems of Reinforcement for Concrete and Similar Structures, of which the following is a specification.

My invention relates to improvements in means for reinforcing masonry structures, and more particularly concrete structures. The reinforcement most commonly used in such structures at the present time consists of smooth steel rods which are embedded in the material of the structure and serve to take up tension in the same, being at the same time protected from deterioration by the surrounding material. This form of reinforcement is especially advantageous on account of the cheapness of the rods, the fact that they are a staple article of merchandise, and the ease with which they may be handled in building them into the structure, since they have sufficient flexibility to permit their being bent into the desired form and sufficient rigidity to retain such form while the concrete or other material is being placed in position. An objection to this type of strengthening means, however, is alleged to exist in the fact that the concrete or other material of the structure may slip upon the rods or other smooth members, and thus cause cracking and weakening of the structure, with the possibility of its ultimate failure. Several plans, therefore, have been proposed for preventing this slipping of the material upon the tension members, among which may be mentioned the use of twisted iron or steel bars, bars with transverse projections or corrugations of various sorts, mesh reinforcements of wires electrically welded together at intersections, expanded metal, &c. Such devices, however, on account of their inherent weakness become impracticable in cases where heavy reinforcements are required and are more expensive than plain reinforcing members. Moreover, they are not usually in economical form and represent some waste in material. Again, in the case of mesh forms of strengthening mediums they are unwieldy and difficult to build into the structure. In all cases they supply more resistance than is necessary simply to prevent slipping.

In my present invention I seek to provide

a reinforcement for concrete structures and the like that shall embody the advantages of both types mentioned above, so far as cheapness, convenience, and non-slipping qualities are concerned, without the disadvantages of either. In accomplishing this object I propose using plain steel or iron forms—such as smooth rods, channel-bars, cables, sheets, or other members of efficient cross-section for resisting tension—as a primary system of reinforcement that shall have sufficient strength to resist the tensile stress to which they may be subjected by the structure. In order to prevent the slipping of concrete on these rods or other parts comprising the primary system and realizing that if the concrete can be held together through the regions of tension it cannot slip on the primary rods or members, I bond the concrete together through these regions of tension by a secondary system of reinforcement, consisting of corrugated rods, twisted rods, wire mesh, expanded metal, or other section designed to prevent slipping, such secondary system preferably following closely the main or primary system and being also preferably attached to the same at intervals for convenience in building the structure. Thus as a main reinforcement I am enabled to utilize the more economical and convenient forms, and only as a secondary reinforcement which requires less material am I required to use members of the more expensive and unwieldy non-slipping type. In this way a sufficient non-slipping quality is imparted to the reinforcement as a whole, and a more efficient and economical system of reinforcement than heretofore results.

My invention is illustrated by the aid of the accompanying drawings, forming a part of this specification, in which the same reference characters are used throughout to designate like parts, and in which—

Figure 1 is a longitudinal sectional view of a beam of concrete or like material reinforced by a primary and secondary system, as above mentioned. Fig. 2 is a cross-section of a similar structure, showing various arrangements of the primary and secondary systems of reinforcing members which may be employed. Fig. 3 is a longitudinal section of an arch embodying the same features. Fig. 4 is a cross-section of a conduit or sewer, showing the improvement supplied thereto; and Figs. 5, 6, 7, and 8 are detail views of

various materials which may be employed in the secondary system.

In Fig. 1, 2 represents a beam of concrete or like material having suitable end supports 3 and 4. In the beam 2 the primary system of reinforcement is indicated at 5, this being a steel tension-rod or sheet of steel or cable or any other desired smooth section capable of resisting the tensile stress. This tension member, as is indicated, passes through the lower edge of the beam 2 at its central portion 6, which is the region of greatest tension in the beam, and its ends curve up toward the upper edges of the beam, as is indicated in the drawings, and may be suitably anchored in any desired way, as by special members embedded in the material of the beam or simply by the adhesion of the material. Another tension member 7 is indicated in this beam, which is located throughout near the lower edge of the same and is capable of resisting tension at all points along said edge. These members 5 and 7 may both be used or they may be used singly and 25 constitute what I have termed the "primary system of reinforcement." Inasmuch as the greatest tension in the beam occurs in the region adjacent to point 6, I bond this portion of the beam together by means of the secondary system of reinforcement 8, which consists of some efficient non-slipping section, such as wire mesh, twisted, corrugated, or other irregular rods, expanded metal, &c., and place the same adjacent the rods 5 and 35 7 through the region of greatest tension. This secondary system prevents the cracking of the concrete and therefore its slipping upon the rods 5 or 7, it being understood that the members 5, 7, and 8 are all embedded in 40 the material of the beam. As a means of conveniently building the structure the said secondary system 8 may be merely laid upon the rods or members 5 or, if desired, it may be wired or otherwise secured thereto to 45 hold it in place, as indicated at 8^a.

In Fig. 2 I have indicated various relative positions for the primary and secondary systems, the numerals 9, 10, and 11 indicating the primary system, and 12 the secondary system associated with the members 9, this secondary system consisting of the mesh form of reinforcement, a sheet of which is placed just above the members 9. In connection with the main members 10 I have shown the 55 secondary system 13 as consisting of twisted square rods located beneath the main members. The secondary system that co-operates with the main members 11 I have indicated as twisted square rods placed above 60 the main tension members 11, and in both of the latter cases I have shown the secondary system as consisting of two rods placed one on either side of the main members. It is obvious that any desired arrangement and 65 position of these main and secondary mem-

bers may be employed, the idea being to in each case so dispose the secondary system that it will bond the concrete together through the regions of tension, so that it cannot crack or give and slip upon the members of 70 the main system.

In Fig. 3 I have indicated this method of reinforcement as applied to an arch, in this instance the arch consisting of a ring 15, supported at its ends upon the abutments 16. I have also indicated the main tension members as a plurality of series of rods 17, 18, and 19, passing alternately across the body of the arch and through the regions of tension at the intrados and extrados, but with 80 the different series crossing the arch-ring at different longitudinal points, an arrangement which is found desirable where the exact location of the tension areas cannot be definitely ascertained. As shown at the center 85 of the arch, I have located the secondary system 20 upon the upper side of the rods 17, 18, and 19 to bond the concrete together at the crown in the intrados, said secondary system preferably following closely the 90 curvature of the main members and of the arch, and over the haunches the secondary system of reinforcement is indicated at 21, said system being placed outside of the rods and following the general curvature of the 95 several series as a whole. It will be understood that this secondary system in all of the locations shown might be arranged in a different manner with respect to the main tension members—as, for instance, by placing 100 the same upon the other side of the said main members—but for convenience in erecting the arch the relative location shown is deemed preferable, since they may be readily attached to the main members, so as to be 105 held in position during the erection of the arch. In this instance, as in the case of Fig. 1, suitable anchorage may be provided for the main members. The secondary system in this instance also effectually bonds the 110 material of the arch through the regions of tension, so that it cannot crack and slip upon the main tension members.

In Fig. 4 there is indicated a still different form of structure, but in which the same 115 method of reinforcement is applied. In this figure the cross-section of a conduit or sewer is indicated at 22 and the main tension member at 23, the latter being disposed to resist tension in the regions of tension in the conduit which is produced therein by vertical pressure. The secondary system which, as before stated, may consist of any efficient non-slipping section, is applied at 24, 25, 26, and 27 to bond the concrete at the various 120 regions of tension and prevent its slipping upon the main tension members 23; but it is evident that such secondary system may be located upon the opposite side of the main members from that shown. 125

Fig. 5 shows a wire mesh 28, which may be employed as the material of a secondary system.

Fig. 6 indicates a twisted square rod 29, which may also be used for this purpose, and in Fig. 7 another non-slipping member is indicated, which consists of a rod provided with transverse projections formed thereon in any desired manner.

10 It is obvious that this method of reinforcement may be applied to various other structures—such as tanks, columns, floors, &c.—and that the arrangement may be varied to suit the different conditions of use.

15 I prefer that the primary reinforcement of my invention be of material having a low elastic limit and the secondary reinforcement of material having a high elastic limit. Thus a low-tension or mild or soft steel may be 20 employed for the primary reinforcement and a high-tension steel for the secondary system.

I claim—

1. A concrete structural member reinforced with main members of mild or soft 25 steel or iron and secondary members of roughened hard steel.

2. A structural member of concrete reinforced with main members of low-tension metal and with secondary members of roughened high-tension metal.

3. A structural member of concrete having embedded therein reinforcing members of smooth low-tension metal crossing from one tension-surface to another, and other reinforcing members of roughened high-tension metal following each surface closely and overlapping the regions of crossing.

4. A structural member with embedded tension members crossing the member alternately at different longitudinal points, and roughened tension members transverse to tension regions.

5. A structural member of concrete with a smooth rod and a corrugated, twisted, or deformed bar of higher elastic limit embedded across a tension region.

6. A structural member having embedded therein smooth bars extending continuously through all the regions of tension and crossing the member at different longitudinal points and roughened bars confined to each tension region.

7. A concrete structural member having main reinforcing members of smooth metal 55 passing through a tension region and beyond to secure anchorage, and other members of corrugated twisted or deformed metal of different elastic limit embedded within the tension region.

8. In a concrete or similar structure, the combination with a primary system of reinforcement of material having a low elastic limit embedded therein, of a secondary system of reinforcement of material having a

higher elastic limit and a roughened or deformed surface, substantially as described.

9. A structural member having embedded therein two kinds of reinforcing members, one having a low elastic limit, the other a high elastic limit.

10. A structural member of concrete having embedded therein a reinforcing member of metal of low elastic limit and another of metal of higher elastic limit.

11. A concrete structural member having 75 embedded therein near one surface roughened and smooth reinforcement, the smooth reinforcement curving away from the roughened reinforcement and across the member at alternating points.

12. A concrete structural member having smooth and rough reinforcing members embedded in a region of tension, the roughened reinforcement continuing along the tension-surface, while the smooth reinforcement 85 curves out of the tension region and across the member, the material of one reinforcement being of higher elastic limit than the other.

13. A structural member of concrete having embedded therein reinforcing members 90 following a tension-surface and curving away from the surface at different longitudinal points, and other roughened reinforcing members continuing along the tension-surface.

14. A structural member of concrete having embedded therein smooth reinforcing members passing from surface to surface across the body of the member at alternating points and roughened members adjacent to the surfaces only.

15. A structural member having roughened members embedded therein near each surface, and smooth reinforcing members passing from near one of the surfaces to the other.

16. A concrete structural member having roughened metal bars embedded therein near each surface separately and smooth reinforcing members passing from near one of the surfaces near to the other surface.

17. A girder, beam or arch of concrete with smooth rods crossing from one tension region to another, and corrugated, twisted or deformed bars confined to a tension region.

18. A girder, beam or arch, with reinforcing members following closely a portion of the unloaded surface, and then crossing to the loaded surface, and other roughened members following one surface closely.

19. A girder, beam, or arch of concrete or similar material having reinforcing members following closely the tension-surfaces, with a corrugated, twisted, or deformed bar embedded in the tension region in a parallel direction.

20. A girder, beam or arch of concrete, reinforced by smooth rods or bars following closely the lower surface, and other smooth

4
bars crossing from the lower surface to the upper, and corrugated, twisted or deformed bars following closely the lower surface.

21. A concrete arch having smooth rods embedded therein, said rods passing near the inner surface and crossing to the outer surface and roughened bars following the inner and outer surfaces separately.

22. A concrete arch having roughened reinforcing members embedded near either surface, and other reinforcing members crossing from near one surface to the other.

23. A concrete arch having roughened bars embedded near intrados or extrados, and other bars crossing from intrados to extrados diagonally across the arch-rib.

24. A concrete arch with corrugated, twisted or deformed bars embedded near both surfaces, and other bars crossing the arch-rib.

25. A concrete arch with roughened reinforcing members near portions of the intrados

and others near portions of the extrados alternately opposite, and smooth reinforcing members passing from one of these regions to the other.

26. A concrete arch with reinforcing members embedded therein passing continuously through all the tension regions, and other roughened members passing through the respective tension regions.

27. In a curved structural member, the combination of a primary system of smooth reinforcement with a secondary system of roughened reinforcement concentrated in the tension regions.

Signed by me at Indianapolis, county of Marion, State of Indiana, in the presence of two witnesses.
